UNITED STATES PATENT OFFICE.

MAURICE C. CLARK, OF PROVIDENCE, RHODE ISLAND, ASSIGNEE TO
MARVEL RUBBER COMPANY, A CORPORATION OF RHODE ISLAND.

APPARATUS FOR MANUFACTURING RUBBER FOOTWEAR.

No. 823,923.

Specification of Letters Patent.

Patented June 19, 1906.

Application filed January 31, 1905. Serial No. 243,540.

To all whom it may concern:

Be it known that I, MAURICE C. CLARK, a citizen of the United States, and a resident of Providence, in the county of Providence, 5 State of Rhode Island, have invented a new and useful Improvement in Apparatus for Manufacturing Rubber Footwear, of which the following is a specification.

This invention is an improvement or modification in apparatus for the manufacture of molded footwear, such as that shown, for example, in Letters Patent of the United States to Weeks and Russell, No. 233,386.

In the accompanying drawings I have 15 shown an apparatus embodying my present invention; but I do not wish to be understood as confining myself to the details thereof, as it is susceptible of many modifications and variations without departing from the scope 20 of my invention.

Figure 1 is a side view of a footwear-last embodying my invention. Fig. 2 is a top view of the same. Fig. 3 is a vertical cross-section of the same. Fig. 4 is a cross-section 25 of the last and shoe in the mold ready for vulcanizing. Fig. 5 is a longitudinal sectional view of the same.

The last shown in Figs. 1, 2, and 3 consists of a substantially inflexible, preferably metallic, portion and a flexible portion provided with means whereby the flexible portion is distended by pressure preferably exerted through the medium of a fluid, such as air. Certain portions of the boot or shoe are vulcanized under the pressure of the inflexible 35 portion of the last in opposition to the mold, while other portions are vulcanized under the yielding pressure of the flexible portion of the last in opposition to the mold. In the 40 form shown the inflexible portion of the last contains the hollow body A, preferably of cast metal, provided with a top opening B and lateral openings C and conforming approximately to the interior of a shoe or boot. It 45 also contains the sheet-metal sole-plate E, secured to the bottom of the body portion A by screws e. The flexible portion of the last consists of a casing D, made in the form of the interior of the shoe or boot and fitting 50 over the outside of the body portion A and extending between it and the sole-plate E, forming an air-tight inclosure for the body A, with the exception of the opening d at the top, which registers with the opening B.

This flexible last member is preferably composed of a combination of cloth and rubber compound and may be made of two thicknesses of cloth with a between layer of rubber compound adapted to stand the heat of vulcanization in repeated use. 55

At the top of the last is secured by the screws f a metal plate F, having an opening G adapted to register with the openings d and B. The flexible member of the last extends between the body A and the plate F, so 60 as to form an air-tight packing. The rigid member of the last thus contains a clamp to hold the inflatable member at the top of the upper and another clamp to hold the inflatable member at the bottom of the upper or 65 sole. It also provides a chamber between these clamps to contain the inflating fluid, such as air. 70

Extending upward from the top of the metal plate F and preferably integral therewith is the extension H, having a channel H' extending therethrough and communicating with the openings G, d, and B. Threaded into the top portion of this extension H is a valve-casing I, having a duct i passing therethrough, and such valve-casing is provided at its upper end with a valve (designated as a whole by J) adapted to cut off the escape of compressed air which it admits. The extension H I extends through and beyond the 75 mold, so that the portion of said extension beyond the mold constitutes a holder by which the last and shoe are held in proper position as the mold is closed. 80

L, M, and M' are a three-part vulcanizing- 90 mold inclosing the last and a considerable portion of the upward extension H. The division-line between the mold-base L and the side parts is substantially at the sole-line, while the division-line between the side parts 95 M and M' is substantially in the central longitudinal line of the boot or shoe. Any suitable means may be employed for opening and closing these mold parts and also for providing them with the requisite heat for vulcanization. 100

The operation is as follows: A shoe or boot K is built of the usual unvulcanized materials for rubber footwear upon the last, as shown in Figs. 4 and 5, or it may be built upon 105 another last and transferred to this one. The top edge k of the shoe or boot will lie against the surface of the plate F, and the sole of the

shoe or boot will lie against the plate E, while all other portions of the shoe or boot will lie against the flexible last member D. The last carrying the shoe is then placed within the 5 mold, as shown in Figs. 4 and 5, the mold is closed, and the vulcanizing heat applied and continued long enough to complete the vulcanization. As soon as the mold is closed air-pressure of, say, seventy-five pounds to 10 the square inch is admitted past the valve J and extends through the passages in the extension H into the chamber of the body A and thence out through the lateral openings C into the space o between the body A and the flexible mold member D, which is distended by such air-pressure so as to exert a 15 sufficient pressure in opposition to the mold to cause the proper vulcanization of the walls of the boot or shoe interposed between it and the mold.

It will thus be seen that the sole of the boot or shoe is vulcanized while under pressure between two solid materials—namely, the plate E and the mold-base L; also, that the edge 25 k of the shoe or boot opening is vulcanized while pressed between two solids—namely, between the edge of the plate F and the mold parts M and M'; but it will be observed that all those portions of the boot or shoe lying 30 between the sole and the edge are vulcanized under the pressure of the flexible material D distended by the elastic force of a fluid, such as compressed air. The solid plate E will be to a certain extent cushioned by that portion 35 of the material D lying between it and the last-body A, so that the plate E may yield slightly toward the body of the last, such yielding being often advantageous in practice.

Having thus described my invention, what 40 I claim as new, and desire to secure by Letters Patent, is—

1. A last containing, in combination, an upper and a lower clamp and an inflatable member extending between said clamps.
2. A last containing a rigid lower pressing member, a rigid upper pressing member, a clamp adjacent to said upper pressing member and an inflatable member secured by said clamp.
3. A last containing an upper pressing

member, a fluid passage through the same, a clamp adjacent to the same, an inflatable member secured to said clamp and a body portion whereby said inflatable member is held toward the sole.

4. A last containing, in combination, a body portion providing a fluid-chamber, an inflatable member surrounding said chamber and means provided on said body portion whereby said inflatable member is held above and below.

5. A last containing, in combination, a rigid body portion, an inflatable member extending around and beneath said body portion and a sole-plate secured to said body portion underneath said inflatable member.

6. A last containing, in combination, a body portion, an inflatable member extending around and underneath said body portion, a sole-plate whereby said inflatable member is clamped to said body portion and a clamp whereby the upper edge of said inflatable portion is secured to said body portion.

7. In combination with the chambered body portion of a last, an upward extension adapted to form a holder for the same and containing a longitudinal perforation connecting with said chamber and an inflatable member secured to and extending around said body portion.

8. A last containing, in combination, a body portion A, a sole-plate E, a top plate F and a flexible casing clamped against said body portion by said plates.

9. A last containing, in combination, a hollow body portion A provided with openings B and C, a flexible covering surrounding said body portion outside of the openings C and means whereby said flexible covering is clamped to said body portion around said opening B.

In testimony whereof I have hereunto signed my name in the presence of two subscribing witnesses.

MAURICE C. CLARK.
